UNITED STATES PATENT OFFICE.

FREDERICK H. MORSE, OF BOSTON, MASSACHUSETTS.

SURFACE ELECTRODE FOR ELECTRICAL THERAPEUTIC APPARATUS.

Application filed December 19, 1921. Serial No. 523,479.

To all whom it may concern:

Be it known that I, FREDERICK H. MORSE, a citizen of the United States, and resident of Boston, county of Suffolk, State of Massachusetts, have invented an Improvement in Surface Electrodes for Electrical Therapeutic Apparatus, of which the following description, in connection with the accompanying drawing, is a specification, like characters on the drawing representing like parts.

This invention relates to surface electrodes such as are used in electrical therapeutic apparatus and it has for its object to provide an improved form of surface electrode in which the pad member of absorbent material is set into a recess formed in the rubber backing, and in which a novel electric circuit terminal is employed which has a swivel construction and by which the operation of connecting the circuit wire to the pad or disconnecting it therefrom is greatly facilitated.

In order to give an understanding of the invention I have illustrated in the drawings a selected embodiment thereof which will now be described after which the novel features will be pointed out in the appended claims.

Fig. 1 is a plan view of a surface electrode embodying my invention.

Fig. 2 is an enlarged sectional view through the electrode.

Fig. 3 is a fragmentary sectional view similar to Fig. 2 but showing the manner in which the circuit wire terminal is disconnected from the electrode terminal.

Fig. 4 is an enlarged sectional view taken transversely through the socket terminal.

The device herein shown is of that type comprising a backing member 1 which is usually of rubber and to which is secured the pad member 2 that is formed of absorbent material enclosed in a suitable cover or envelope 3 and means for connecting a circuit wire to the pad member so that when the pad member is moistened and placed on any portion of the body and connected to an electric circuit the patient will receive the desired electrical treatment.

One object of my invention is to provide a novel way of attaching the pad member 2 to the backing 1. The backing 1 is shaped to provide a recess 4 in which the pad is received so that the face 5 of the pad which is placed against the patient comes substan-

tially flush with the edge 6 of the backing 1.

The pad is retained in place in any suitable way as by means of stitching or fastening devices 7.

This construction has the advantage that the pad member is securely retained in place by reason of being received in the recess 4.

In devices of this sort it is desirable that the rubber backing 1 should extend beyond the pad member so as to protect the latter at its edges and where the backing is formed with a recess 4 in which the pad member is received the projecting portion 6 of the backing comes substantially flush with the face of the pad thus obviating the presence of a shoulder at the edge of the pad, such as would be formed if the pad were secured to a flat backing member.

In the drawings 8 indicates a circuit wire which is connected to a terminal secured to the pad member, and a common method of securing the circuit wire to the pad member is to provide the latter with a terminal post having a transverse aperture and to provide the circuit wire with a metal tip adapted to be inserted into the aperture. One disadvantage of this construction is that there is the possibility that the tip will be pulled out from the aperture during the use of the pad thus breaking the electrical connection.

I have provided herein an improved construction in which the circuit wire 8 is connected to the pad with a swivel connection 90 so that the circuit wire can be turned in different directions relative to the pad without danger of breaking the electrical connection.

The pad terminal comprises a metal plate 9 overlying the back face of the backing 1 and fastened thereto by means of prongs or feet 10 which are inserted through the backing and through the envelope of the pad, said feet being clinched over onto an electrode member 11 located within the pad member 3. This plate 9 has secured thereto a socket member 12 which is adapted to receive a circuit wire terminal plug member 13 to which the circuit wire 8 is connected. This plug member 13 has rigid therewith two arms 14 and 15 extending in opposite directions, the arm 15 being electrically connected to the circuit wire 8.

Situated within the socket member 12 is a split clamping ring 16, the edge 17 of the socket member being spun over to partially enclose the ring and thereby hold it in

place. The plug member 13 is formed with an enlarged inner end 18 which is adapted to snap into and be embraced by the clamp-ring 16.

5 The construction is such that the circuit wire may be connected to the pad member by merely pressing the plug terminal into the socket terminal, the resiliency of the split ring 10 permitting this operation. When 10 the electrical connection is thus made the plug terminal is free to rotate in the socket terminal so that the circuit wire 8 may be led in the direction as shown in full lines Fig. 1 or that shown in dotted lines Fig. 15 1 or in any other direction, and this turning of the plug terminal in the socket terminal may be accomplished without in any way tending to disconnect the two terminals. This is very convenient because in using the 20 device the pad is frequently manipulated or moved from one location to another and the swivel connection permits this to be done without danger of breaking the electric circuit.

25 To disconnect the plug terminal from the socket terminal it is simply necessary to pull the arm 15 away from the backing member as shown in Fig. 3. When this is done the end of the arm 14 bears against 30 the plate 9, the latter acting as a fulcrum as shown in Fig. 3, and as the structure comprising the arms 14, 15 and the plug terminal 13 is a rigid structure, the swinging movement of the arm 15 away from the pad 35 will withdraw the plug terminal 13 from the split ring 16.

The central portion 21 of the plate 9 to which the socket member 12 is secured is depressed so that the socket member comes 40 substantially flush with the back face of the pad. The arm 14 is of sufficient extent to overlie the portion 20 of the plate 9 which is not depressed so that with this construction a slight swinging movement of the terminal will bring the end of the arm 14 45 against the flat part of the plate 9.

Moreover the construction is such that the plug terminal can be disconnected from the socket terminal equally well in any angular position of the arms 14 and 15 because in all positions the arms 14 and 15 overlie the flat portion 20 of the plate 9.

I claim.

65 1. In a surface electrode for an electrical therapeutic apparatus, the combination with a rubber backing, of a pad of absorbent material secured thereto, said pad having a recess in its back face and the rubber backing having an opening aligned with the

60 recess, a socket terminal member secured to the pad and occupying the recess, said terminal member coming substantially flush with the back, a plug terminal member for detachably engaging the socket terminal member, said plug terminal member having 65 a terminal arm rigid therewith and extending parallel to the back face of the pad and to which the circuit wire is secured.

2. In a surface electrode for electrical therapeutic apparatus, the combination with 70 a rubber backing member having a pad-receiving recess and a flange surrounding said recess, of a pad member of absorbent material situated within the recess and having its face coming substantially flush with said flange, a socket terminal in the back of the electrode situated below the surface thereof and a plug terminal detachably fastened to said socket terminal.

3. In a device of the class described, the 80 combination with a pad, of a socket terminal member secured thereto and provided with a split clamping ring, a plug terminal member to enter the socket member and adapted to be detachably clamped by said ring, and a circuit wire connected to the 85 plug terminal member.

4. In a device of the class described, the combination with a pad member, of a plate 90 secured thereto and having a depressed central portion, a socket terminal secured to said depressed central portion, a plug terminal member adapted to enter and be detachably secured to the socket terminal member, said plug having two oppositely-extending arms overlying the plate and the arms and plug member constituting a rigid structure and a circuit wire connected to one of said arms, the other arm being constructed to bear against the plate when said rigid structure is moved into an angular relation to disconnect the plug terminal from the socket.

5. In a surface electrode for an electrical therapeutic apparatus, the combination with 105 a rubber backing member, of a pad of absorbent material secured thereto and having a recess in its back face, a socket terminal located in said recess with its axial line extending transversely of the pad, and a 110 plug terminal member comprising a rigid arm extending parallel to the back face of the pad and a plug member rigid with said arm and swivelled in the socket member to turn about the axial line thereof.

In testimony whereof, I have signed my name to this specification.

FREDERICK H. MORSE.
